UNITED STATES PATENT OFFICE

122,231

DESIGN FOR A CLIP OR SIMILAR ARTICLE

Anne Glass, New York, N. Y.

Application July 25, 1940, Serial No. 93,920

Term of patent 3½ years

To all whom it may concern:

Be it known that I, Anne Glass, a citizen of the United States of America, residing in New York city, county of New York and State of New York, have invented a new, original, and ornamental Design for a Clip or Similar Article, of which the following is a specification, reference being had to the accompanying drawing, forming part thereof, wherein,

I claim:

The ornamental design for a clip or similar article, substantially as shown.

ANNE GLASS.
